LOCKING MEANS FOR FOLDING
LARYNGOSCOPES

Charles S. Cook, Sennett, and Harry L. Becker,
Auburn, N. Y., assignors to Welch Allyn, Inc.,
Auburn, N. Y., a corporation of New York

Application June 23, 1950, Serial No. 169,918

12 Claims. (Cl. 128—6)

1 The present invention relates to laryngoscopes, and more particularly, to an improved joint connection between the blade and the handle of such type of instrument.

Laryngeal speculums are employed by members of the medical profession for depressing the epiglottis at the base of the tongue, for illuminating the larynx for diagnostic or therapeutical purposes, for performing intra-nasal or intra-tracheal intubations, or for any other reason that requires access to and/or illumination of the posterior oral cavity, larynx, pharynx, or elsewhere, as necessary in each individual's case.

It is desirable in diverse cases to have a laryngoscope that is capable of relative angular adjustment of the handle and blade, so that the therapist may approach the patient from different angles as may be required.

It is also desirable that the laryngoscope be foldable so as to occupy a minimum of space when not in use, and that various parts thereof be readily separable for purposes of cleaning and sterilization.

Therefore, it is an object of this invention to provide a laryngoscope having means for varying the angle of the laryngeal blade relative to the handle of the instrument, and positively locking the same in the various positions of angular adjustment.

Another object of this invention is to provide a laryngoscope that is so constructed as to permit the laryngeal blade to be moved from any of its various positions of angular adjustment to a position closely adjacent to the handle of the instrument.

A further object of the invention is to provide a laryngoscope that is so constructed as to permit the blade section thereof to be readily and simply detached from the handle section.

A still further object of the invention is to provide means associated with the relatively adjustable and separable blade and handle portions, for automatically effecting energization of the light source, usually mounted at one end of the laryngeal blade, when the blade is in an operative position relative to the handle, and conversely, effecting de-energization of said light source incident to movement of the blade to an inoperative position closely adjacent to the handle of the instrument.

These and further objects and advantages ascribed to the novel joint or connection between the handle and blade portions of the instrument of this invention, will become apparent from the following detailed description and draw-

2 ings forming a part of this application, and the novel features thereof defined in the appended claims.

In the drawings:

5 Figure 1 is a view in side elevation of a laryngoscope embodying one form of improved hinge joint of this invention, and showing in dotted lines the various positions of adjustment of the blade, with the joint cap removed;

10 Figure 2 is a fragmentary view in end elevation of the joint and adjacent parts of the instrument of Figure 1;

Figure 3 is an enlarged view in vertical section as taken on the line 3—3 of Figure 1, certain of the parts being shown in elevation;

Figure 4 is a view in vertical section taken on the line 4—4 of Figure 3;

Figure 5 is an enlarged view in horizontal section taken on the line 5—5 of Figure 1, with part of the plunger pin shown in plan, and other parts of the pin broken away;

Figure 6 is a view in vertical section as taken on the line 6—6 of Figure 2;

Figure 7 is a composite view of the two separable joint members in a disjointed condition, and showing the inner, complementary interlockingly engageable portions thereof in elevation and in position for inter-engagement when they are turned to face each other;

Figure 8 is an exploded view of the joint construction, with parts of the female section thereof shown in vertical section;

Figure 9 is a view in vertical section, taken on the line 9—9 of Figure 10, of a modified form of a joint according to this invention, with a portion of the male part broken away;

Figure 10 is a view in vertical section as taken on the line 10—10 of Figure 9, with certain of the parts shown in elevation and others broken away;

Figure 11 is a composite view of the two separable joint members, of the modified form shown in Figure 9, with the joint members in a disjointed condition, and showing the inner, complementary interlockingly engageable portions thereof in elevation, and in position for inter-engagement when they are turned to face each other;

Figure 12 is a view in top plan of the male portion of the modified joint of Figures 9 to 11; and

Figure 13 is a view in perspective of the positioning ring which forms a part of both forms of this invention.

Like reference characters designate corre-

sponding parts in the several figures of the drawings, wherein the laryngoscope as seen in Figure 1 comprises a handle member 1 and a blade member 2, which members are interlockingly, detachably and adjustably interconnected by means of the novel joint construction 3, which will hereinafter be described in detail.

Suitably attached adjacent to one end of the laryngeal blade 2 is a head member 4 which is generally frusto-conical in shape, the free end of this head member forming the female portion of the joint 3, and the head member and blade forming a blade unit.

The handle 1 of the instrument is adapted to receive an upwardly tapering base member 5, the free extremity of which forms the male portion of joint 3, and the handle and base portion forming a handle unit.

The details of construction of the adjustable and separable joint 3 will now be described.

The free end of the hereinbefore mentioned head member 4 is provided with an enlarged hollow cylindrical joint member 6 having the axis of the cylinder disposed at right angles to the axis of the head member 4, the cylindrical member 6 being offset laterally, whereby one face thereof is substantially flush with the central axis of the head as best shown in Figure 8.

Internally of the cylinder 6 and towards the inner end thereof the opening therethrough is reduced in diameter to form a shoulder 7, and an opening or bore of a lesser diameter 7'.

Suitably secured in close fitting relationship to the shoulder 7 is a locking or positioning ring 8, said ring being provided with a plurality of radial, spaced, diametrically opposed locking or positioning recesses 9 therein, and a pair of diametrically opposed radial slots therethrough as indicated at 10.

Inwardly spaced from the shoulder 7 of the cylindrical member 6, the inner face of the reduced bore 7' is provided with an annular groove 11 and a pair of diametrically opposed slots 12 entering the groove, these slots 12 extending longitudinally to the inner face of the cylindrical member 6, and forming a so-called bayonet slot.

A closure cap 25' is suitably positioned in the open outer end of the cylindrical portion 6, as by a tight slip fit, as indicated at 6'.

Detachably interconnected with the hereinbefore described female portion 6 of the joint 3, and angularly adjustable relative thereto, is a male portion of the joint, which comprises a second substantially hollow cylindrical enlargement 13 at the upper end of the base member 5. This cylindrical part 13 also has its central axis disposed at right angles to the axis of the base member 5 and is laterally offset therefrom so as to have the inner face of the cylinder substantially flush with the axis of said base member, as best shown in Figure 8.

Extending coaxially with and inwardly from the cylindrical portion 13 is a second cylindrical portion 14 of reduced diameter, the two coaxially extended cylinders having a common bore or opening therethrough as indicated at 15.

The base member 5 is provided with a shoulder 5' vertically spaced from the cylindrical projection 14 a sufficient distance to permit of receiving the lower portion of the cylindrical member 6 therebetween, upon assembly of the respective joint parts.

The reduced cylindrical projection 14 is of a size to be closely but freely rotatably received

in the reduced portion 7' of the head section 6 of the joint, and is provided with a pair of diametrically opposed, radially projecting pins 16 adapted to cooperate with the groove 11 in the opposite member 6 for preventing relative lateral play between the two sections when angular adjustment of the joint is being effected.

The reduced cylindrical member 14 is also provided with a pair of radial, diametrically opposed slots 17 extending substantially the full length of the member.

The outer or righthand end, as seen in Figure 8, of the cylindrical joint member 13, is provided with an annular groove or recess 18 adapted to receive therein the inner convolution of a compression spring 19.

A pin or plunger 20 of a diameter slightly less than the bore 15 of the base section 5 is received in the bore and is shiftable endwise therein, said pin 20 being provided at one end thereof with a locking or positioning key 21 and a second key 22 cooperatively engageable with the slot 17 in the member 14 for preventing rotation of the pin 20 in the bore 15, as will be hereinafter more fully described.

The other end of the pin 20 is provided with a reduced, screw-threaded portion 23 engageable for purposes of assembly with the tapped projection 24 of a plunger button or cap 25. The cap 25 has an annular recess 26 therein for accommodating and seating the compression spring 19. A chordal recess 27 is located in the side wall of the cap 25, and will be more fully described as the description progresses.

The instrument is provided with suitable means for energizing a light bulb 28 carried at the extreme outer end of the blade 2, when the blade is in any of its various operative positions, and for deenergizing the light bulb when the blade is in its inoperative position or in the position permitting of separation of the adjustable joint, the operative positions being designated in Figure 1 of the drawings as A, B and C, and D designating the disengaging or separable position, and E designating the folded or inoperative position.

The means for effecting the energization or deenergization of the light source 28, includes a suitable number of flashlight batteries 29 carried in the handle 1, as is customary in the art, the handle being fitted to the base member 5, as at 30. Electrical contact with the batteries 29 is made by means of a contact member 31 suitably positioned in a vertical bore 32 in the base member 5 and insulated therefrom, so as to be engageable with battery contact 33. An opening or passage 34 is also provided in the base member 5 and extends upwardly through the cylindrical portion 13 thereof, as best seen in Figure 6. Electrical conductive insulated wire 31' extends from the contact 31 through the passage 34 and is connected to a contact shoe 35. This contact shoe 35 is mounted in an insulating member 36 suitably secured as by means of screws 37 in a groove 38 formed in an arc of the periphery of the cylindrical member 13.

Adapted for cooperation with the contact shoe 35, to complete the circuit to the light source 28 is a spring loaded ball contact 39 which is suitably positioned in an insulating block 40, the insulating block being secured in a groove 41 in the head member 4, as by means of screws 40'. Centrally of the groove 41 is a vertically extended opening 42 for receiving the hollow spring accommodating section 43 of the insulating block 40.

As best seen in Figures 3 and 8, the ball contact

39, contact shoe 35 and their respective insulating blocks and fastening means are so located in the head 4 and the base 5 respectively of the assembly that they do not interfere in any way with the lateral separation of the two parts which form the joint 3.

Connected to the ball contact assembly 39, and passing upwardly through the head 4 is a second section of conductive, insulated wire 44, which is passed to the exterior of the head member in the area adjacent the juncture of the head 5 and the blade 2, as at 45 (Figure 1) and then leads through a tube 44' to the light 22. Ground contact for the other side of the circuit is made through the metal parts of the instrument.

While the instrument of this invention has been shown and described as carrying batteries in the handle, it is within the purview thereof to have a house current connecting means carried by the handle in lieu of the batteries.

The assembly of the hereinbefore described components will now be described.

The pin 20 is passed through the bore 15 in the base portion 5, the key 22 sliding into the slots 17 of the member 14 and preventing relative rotation of these parts. The compression spring 19 is then positioned in the annular groove 18 in the cylindrical member 13 and the plunger button or cap is threaded into position on the pin 20.

The outer diameter of the annular recess 26 in the cap 25 is preferably of a size whereby the cap may overlap the marginal edge of the cylindrical member 13, as seen in Figure 3. The arcuate recess 27 in the edge of the cap 25 is provided for permitting of relative reciprocating movement of the pin 20 relative to the base 5 without interference from the cap, as is apparent in Figures 3 and 10.

The mating joint member 6, forming a part of the head 4, may now be connected with the base joint member 14 when the parts are in a position relative to each other as designated D in Figure 1, the key 21 passing through the slots 10 in the locking ring 8 and the pins 16 entering the slots 12 into the groove 11.

Now it is apparent that sufficient pressure applied inwardly on the plunger button 25 will shift the pin 20 laterally in the direction of pressure to a point where the positioning or locking key 21 is in a position laterally past the outer face of the locking ring 8. Clockwise rotation of the head 4 relative to the base 5, as viewed in Figure 1, will cause corresponding rotation of the key 21 and the pins 16 relative to the locking ring 8 and the groove 11 respectively, this clockwise relative rotation being limited by the abutment of the blade 2 against the handle 1, as seen in position F in Figure 1. The positioning or locking key 21 will now be out of alignment with the slots 10 in the locking ring, and therefore the joint is positively secured against relative lateral disconnection.

Relative lateral play between the two joint members during the angular adjustment hereinbefore described is prevented by means of the pins 16 riding in the groove 11. Moreover, disengagement of the locking key 21 from the locking ring 8 upon lateral movement of the pin 20 is assured, as movement of the entire head section 4 along with the pin 20, as it normally tends to do, is prevented.

The contact shoe 35 and the ball contact 39 are so positioned when the assembly is in positions D and F that the ball 39 is in contact with

the insulating member 36. Therefore no energization of the lamp 28 is effected in these respective disengaging and inoperative folded positions.

Upon reverse or counter-clockwise relative rotation of the head and base members, the positioning key 21, incident to the release of pressure on the button 25, selectively seats in one of the grooves 9 in the locking ring 8, thereby locking the blade and handle sections of the laryngoscope against inadvertent relative rotation in either direction.

It is apparent that upon counter-clockwise relative rotation of the head and base, that the ball contact 39 will ride up on the contact shoe 35, thereby energizing the lamp 28 in all of the operative positions of the instrument.

The modified form of the invention shown in Figures 9 through 12 is the same in function as the preferred form hereinbefore described, and the construction of the respective elements of the laryngoscope are identical in most respects, and therefore have been given the same reference characters, except for those modified parts which have been primed, and will now be described.

The only difference between the previously described form and the modification is that, as best seen in Figures 11 and 12, the groove 11' and slot 12' are formed in the peripheral surface of the reduced cylindrical extension 14 of the base member 5. Instead of being an annular groove, the groove 11' constitutes only an arc of the annulus, the opposite ends of the groove being cooperative with the pin 16', carried by the reduced portion 7' of the head section 4, to effect a limit stop, whereby the degree of relative angular adjustment of the joint is limited by the length of said groove. The extremity 16'' of the groove 11' is so located as to form a stop when the head and base sections are in axial alignment, as seen in Figure 9.

It will be readily apparent that laryngeal blades of different types and/or sizes may be easily and quickly interchanged for use with a common base or battery handle when the blade sections and base sections are provided with detachable and adjustable hinge joints as hereinbefore described. This is particularly desirable since these laryngoscopes are used for patients of various ages ranging from small children to adults.

In the use of the laryngoscope, it is only necessary to hold the blade section of the instrument in the relative position designated D in Figure 1, slip the mating portions of the two joint sections into interengaging relationship, apply thumb pressure to the plunger button or cap 25, and rotate the joint parts relative to each other to the desired selective operating position of the blade, the light being automatically energized when the contacts 39 and 35 are brought into contacting relationship incident to the relative rotation of the base and head sections. Upon release of the thumb pressure aforesaid, the blade is positively and automatically locked in position by virtue of the locking key 21 seating in one of the grooves 9 of the locking ring 8.

While the specific details have been shown and described herein, our invention is not confined thereto as changes and alterations may be made without departing from the spirit thereof as defined by the appended claims.

We claim:

1. A laryngoscope, comprising a handle section, a blade section, and means hingedly connecting the sections, said means comprising a hinge joint 75 which includes complemental, relatively rotatable

members carried by the respective handle and blade sections and separably interengaged with each other with said blade section angularly adjustable relative to said handle section, cooperatively interengaged means within said hinge joint for positively locking said blade section in selective adjusted positions and for interlocking said sections together in said adjusted positions, said cooperatively interengaged means being disengageable when said sections are in one predetermined position relative to each other for separating said sections, and cooperative means in said hinge joint interlocking the sections against relative lateral movement while the sections are being relatively angularly adjusted.

2. A laryngoscope, comprising a handle section, a blade section, hinged interconnecting means therebetween, said means comprising a hinge joint and including complementary, relatively rotatable members carried by the respective handle and blade sections and separably interengaged with each other with said blade section angularly adjustable relative to said handle section, cooperatively interengageable means within said hinge joint for positively locking said blade section in selective adjusted positions and for interlocking said handle and blade sections together in said adjusted positions, said cooperatively interengaged means being disengageable when said sections are in one predetermined position relative to each other for separating said sections, cooperative groove and pin means in said hinge joint for preventing relative lateral movement between said sections while the sections are being relatively angularly adjusted.

3. A laryngoscope as defined in claim 2, wherein in the cooperative groove and pin means in said hinge joint for preventing relative lateral movement between said sections, comprises pin means carried by one of said complementary members, and a groove in the other of said complementary members.

4. A laryngoscope as defined in claim 2, wherein in the cooperative groove and pin means in said hinge joint for preventing relative lateral movement between said sections, comprises a pair of radially extended pins on one of said complementary members, and an annular groove in the other of said complementary members.

5. A laryngoscope as defined in claim 2, wherein in the cooperative groove and pin means in said hinge joint for preventing relative lateral movement between said sections, comprises a radially directed pin on one of said complementary members, and an arcuate groove in the other of said complementary members.

6. A laryngoscope as defined in claim 2, wherein the complementary, relatively rotatable members comprise a female part substantially cylindrical in form, a mating part having a cylindrical enlargement and a coaxially extended reduced cylindrical projection insertable in the female part aforesaid, said cylindrical enlargement and cylindrical projection having a common bore therethrough, and wherein the cooperatively interengaged means comprises a plunger pin reciprocably positioned in said common bore, means for preventing rotation of said plunger pin in the bore, a locking ring secured internally of the female part aforesaid, said locking ring having a plurality of radially disposed grooves therein, a key carried by one end of the plunger pin aforesaid and engageable in said radially disposed grooves for effecting positively locked adjustable positioning of the complementary, rela-

tively rotatable members, and means normally urging said key into engagement with said radially disposed grooves.

7. A laryngoscope as defined in claim 6, wherein in the means for preventing rotation of the plunger pin in the bore comprises a slot in one of the complementary members extending radially from said bore, and a key carried by said plunger and pin and slidably in said slot.

8. A laryngoscope of the class described, comprising a head member, a base member, an angularly adjustable, separable hinge joint interconnecting said head and base members, said hinge joint including complementary, relatively

rotatable members, a reciprocatable pin passed through said complementary members and having means cooperative with one of the complementary members for preventing relative rotation thereof while permitting reciprocatable movement of said pin, a locking ring in the other of said complementary members, a locking key carried by one end of the pin, said key being interlockingly engageable in at least one position with said locking ring for effecting positively locked angular adjustment of the head and base members aforesaid, complementary groove and pin means in the respective complementary members aforesaid for preventing relative lateral play between said complementary members during relative rotation thereof, slots in the locking ring and slots also in the complementary member having the groove aforesaid, for passage of the locking key and complementary pin respectively therethrough, thereby permitting of lateral separation of the relatively rotatable, complementary members when in a single predetermined position relative to each other and preventing said separation in every other relative position, and circuit closing means carried by said relatively rotatable members adapted for closing a circuit automatically upon relative rotation of said members in one direction, and opening said circuit automatically upon reverse relative rotation thereof to a predetermined position.

9. An angularly adjustable and separable joint connection, comprising a pair of relatively rotatable, complementary members, means separably connecting said members together, one of said members being provided with a locking ring and the other of said members being provided with a shiftable hinge pin therethrough, said hinge pin having means for selective interengagement with said locking ring in a plurality of positions and positively locking said joint in the desired angularly adjusted position, and means for biasing the means on the hinge pin into inter-engagement with said locking ring, said locking ring being provided with an opening therethrough for permitting disengagement of said means on the hinge pin and said locking ring with attendant lateral separation of said complementary members in a single predetermined position while preventing separation in every other relative position of the members aforesaid.

10. An angularly adjustable and separable joint connection as defined in claim 9, wherein the hinge pin has means slidably interengageable with its complementary member for preventing relative rotation of the pin with respect to its complementary member.

11. An angularly adjustable and separable joint connection, comprising a pair of relatively rotatable, complementary members, one of said members being provided with a locking ring and the other of said members being provided with a

hinge pin therethrough, said hinge pin having means for interlocking inter-engagement with said locking ring in at least one position and positively locking said joint in such angularly adjusted position, means for biasing said means on the hinge pin into inter-engagement with said locking ring, a pin-receiving bayonet slot in one of said members and a pin on the other member interengageable in said bayonet slot for preventing relative lateral play between said members when they are being rotated relative to each other, said locking ring being provided with means for permitting lateral separation of said complementary members in a single predetermined position, while preventing separation in every other relative position of the members aforesaid.

12. An angularly adjustable and separable joint connection, comprising a pair of relatively rotatable, complementary members, one of said members being provided with a locking ring and the other of said members being provided with a hinge pin therethrough, said hinge pin having means for selective interengagement with said locking ring in a plurality of positions and positively locking said joint in the desired angularly adjusted position, means for biasing said means on the hinge pin into inter-engagement with said locking ring, a pin-receiving bayonet slot in one of said members and a pin on the other member interengageable in said bayonet slot for prevent-

10
15

ing relative lateral play between said members when they are being rotated relative to each other, said locking ring being provided with means for permitting lateral separation of said complementary members in a single predetermined position, while preventing separation in every other relative position of the members aforesaid, and electrical circuit closing means carried by the complementary members aforesaid and adapted to make electrical contact incident to relative rotation of the members in one direction past a predetermined position and conversely to break said electrical contact incident to reverse relative rotation of said members past said predetermined position.

CHARLES S. COOK.
